CLAIM

The ornamental design for a soup bowl or similar article, as shown and described.

DESCRIPTION

FIG. 1 is a front elevational view of a soup bowl or similar article showing my new design, the rear elevational view is a mirror image thereof;

FIG. 2 is a right side elevational view thereof, the left side is similar with the handle being omitted therefrom;

FIG. 3 is a top plan view thereof;

FIG. 4 is a bottom plan view thereof; and

FIG. 5 is a cross-sectional view taken along line 5—5 in FIG. 3.
